UNITED STATES PATENT OFFICE.

HARVEY FREDERICK, OF NEWARK, NEW JERSEY.

ADVERTISING DEVICE.

Application filed February 15, 1927. Serial No. 168,285.

My invention relates to a new and useful calendar and more particularly to an advertising calendar, which, in addition to serving the purpose of conventional calendars, is also adapted for the effective advertising and display of merchandise.

It has been the general practice heretofore, for the desired advertising matter, such as the name and address of the manufacturer or dealer, or the name of the product, to be displayed on the face of the calendar, either on the calendar sheets proper, that is, the sheets showing the current dates, or on the back or support to which such calendar sheets are usually secured. While this form of advertising calendar served to disseminate some general information about the subject matter of the advertisement, it was disadvantageous in that it made no provision for the visual display and advertising of the particular articles to be advertised.

It is the object of my invention to provide a novel calendar which, in addition to disseminating any desired information about the merchandise to be advertised, such as paints, leather, fabrics, paper and the like, will also visually place before the prospective customer, for an entire year, the actual physical qualities of said merchandise so advertised, such as the approximate colors, texture, weight and thickness.

Another object of my invention is to provide an advertising calendar of the character stated, which will not only serve visually to display the actual samples of the merchandise advertised and give any desired information with respect thereto, but will also serve to keep actual samples of the merchandise conspicuously in view throughout the entire year that the calendar may be in use.

My invention further contemplates the provision of a novel advertising calendar of the character stated, intended for distribution by manufacturers and dealers so desiring to advertise their wares, thus affording an inexpensive and effective method of direct advertising.

To the above ends my invention consists in providing a calendar with a plurality of auxiliary sheets placed back of or beneath the calendar sheets and having the advertising matter to be displayed visually carried by the peripheries thereof, in such a manner that the same will be exposed to view at all times simultaneously with the calendar

sheets without in any way obscuring the latter.

My invention further consists in providing a key, index or other table of information explanatory of or supplemental to the advertising matter displayed, such index or table being disposed upon the body portion of said auxiliary advertising sheets and suitably identified therewith by the use of corresponding indicia.

For the purpose of illustrating my invention, I have shown, in the accompanying drawings, a form thereof, which is at present preferred by me, since it will give, in practice, satisfactory and reliable results, although it is to be understood that the various instrumentalities of which my invention consists can be variously arranged and organized and that my invention is not limited to the precise arrangement and organization of these instrumentalities as herein shown and described.

In the accompanying drawings:

Figure 1 represents a front elevation of an advertising calendar, embodying my invention.

Figure 2 represents a vertical section on line 2—2, Figure 1.

Figure 3 represents a perspective view of the advertising calendar seen in Figure 1 with the calendar sheets removed.

Referring to the drawings, in which like reference characters indicate like parts, 1 designates an advertising calendar embodying my invention, comprising the back or other support 2 and the calendar sheets 3 secured thereto by the fastening means 4. A loop 5 or the like, passed through a hole in the top of the back 2, may be employed to hang the calendar in place in the usual manner.

Referring now particularly to Figure 3 of the drawings, from which the front calendar sheets 3 have been omitted, 6 and 7 designate auxiliary advertising sheets suitably secured to the back 2. To the periphery of the sheets 6 and 7 are secured the sample strips 10 of the articles to be advertised, such as paint, leather, cloth, wall paper or the like. On the central body portion of the advertising sheets 6 and 7 may be displayed the name and address of the manufacturer or distributor as at 8, and the stock or style number, size, price and other tabulated information as at 9. The sample strips or tabs generally

110

designated by the numeral 10 are in practice specifically designated by any suitable indicia such as the numerals 1, 2, 3, 4, etc. Thus, when any information is desired with respect to any one of the suitably numbered or otherwise designated sample strips 10, it is only necessary to raise the calendar sheets 3 slightly and then to look in the table of information 9 under the corresponding number, 10 as for instance, by looking in the table of information 9 under the numeral 1, the size, grade, price, and other information with regard to the particular sample strip numbered 1, is obtained.

15 While in the particular illustration shown in Figure 3, I have employed but two such auxiliary advertising sheets 6 and 7, it is to be understood that any number of such sheets may be employed, for advertising the 20 different samples of one or more species of merchandise. Similarly, the use of my novel calendar is not restricted to the advertising of any particular article herein enumerated, but may be adapted for the advertising 25 and display of any desired article. Thus, for instance, if it is desired to display paints, suitable tabs or strips of material 10, colored with the particular paints or pigments are secured to the periphery of the advertising 30 sheets 6, and 7, substantially as shown in Figures 1 and 3. In like manner, the tabs 10 may consist of actual specimens of the leather, paper, textile or other fabric, or other commodity advertised.

35 By placing the auxiliary advertising sheets 6 and 7 back of or behind the calendar sheets 3, the sample strips 10 designated specifically by proper indicia such as the numerals 1, 2, 3, etc., of the products so advertised, are at 40 all times visible simultaneously with the calendar sheets without in any way obscuring the same. Furthermore, the advertising sheets 6 and 7, bearing the advertising matter will remain in effective use throughout 45 the entire year, since they are not subject to

destruction or removal until the last calendar sheet, such as the sheet for the month of December, or for the last week or day thereof has been torn off and the whole calendar for that particular year has been utilized and discarded. It will be apparent that the same common fastening means 4 may be employed for securing the calendar sheets and the rear advertising sheets to the back 2 as will be understood from Figure 2.

50

55

It will thus be seen that my novel advertising calendar is particularly valuable in advertising such goods as paints, leather, textile fabric, paper and similar articles, since it brings the actual quality, texture and color of the article advertised, visually to the attention of the prospective consumer in a forcible and effective manner for an entire year, and at a minimum cost. It will further be apparent that my novel device is 60 equally adaptable to perpetual calendars so that the specimens of the goods or merchandise thus displayed or advertised will be prominently in view for an indefinite period, or so long as the perpetual calendar is in use. 70

90

Having thus described my invention, what I claim as new and desire to secure by Letters Patent is:—

An article of the character stated, comprising a thin, relatively flat support, arranged to receive conventional calendar portrayals, a leaf having a table of information thereon, said leaf being secured at its top only to said support, and specimens of goods to be advertised fixed along the free marginal edges of said leaf and projecting in both horizontal and vertical manner therefrom, and an additional leaf secured at its top only to said support and arranged to cover said first mentioned leaf and concealing the attachment portions of said specimens but being of such size as to permit the projected ends of said specimens to be visible at all times.

HARVEY FREDERICK.
